UNITED STATES PATENT OFFICE.

PHILIP T. DODGE, OF WASHINGTON, DISTRICT OF COLUMBIA, ASSIGNOR
TO MERGENTHALER LINOTYPE COMPANY, A CORPORATION OF NEW
YORK.

LINOTYPE-MACHINE.

SPECIFICATION forming part of Letters Patent No. 739,996, dated September 29, 1903.

Application filed June 10, 1903. Serial No. 160,838. (No model.)

To all whom it may concern:

Be it known that I, PHILIP T. DODGE, of Washington, District of Columbia, have invented a new and useful Improvement in 5 Linotype-Machines, of which the following is a specification.

My invention relates to improvements in the Mergenthaler Linotype-machine of commerce, having the general construction and 10 arrangement of parts represented in United States Letters Patent No. 557,000, wherein the slug or linotype is cast in a slotted mold mounted in a vertical and intermittently-rotating wheel. The mold stands in a horizontal 15 position during the casting operation, after which the wheel turns, carrying the mold and the base of the slug past a fixed trimming-knife, which determines the height of the slug, the motion continuing until the mold stands 20 in a vertical position with the contained slug directly in front of an ejector-blade which advances from the rear, pushing the slug or linotype before it out of the mold and between stationary knives for trimming its 25 outer side faces into a receiving-galley at the front. The slugs, which frequently adhere tightly to the interior of the mold, must be trimmed with extreme accuracy. In the machines heretofore constructed it frequently happened that 30 the pressure applied by the ejector to expel the slug would cause the mold-wheel and mold to spring forward, the result being an increased resistance to the delivery of the slug and the presentation of the slug inaccurately 35 to the trimming-knives and sometimes a permanent springing of the wheel, so that the base of the mold was not carried closely against the rear knife. The molds are commonly built up of a body portion screwed to the 40 wheel, a vertically-adjustable cap portion, and two intermediate liners which determine the width and length of the slot, and thereby the thickness and length of the slug.

In practice the pressure applied to eject a 45 strongly-adhering slug tends to loosen or displace the mold in relation to the disk and to disturb the proper relations between the cap, body, and liners. The parts are also disturbed occasionally by the pressure of the 50 ejector-blade if it chances to be out of adjust-

ment. To overcome these difficulties, I provide a rigid banking surface or surfaces, against which the mold is rigidly supported at the front during the ejection of the slug.

Referring to the drawings, Figure 1 represents a horizontal section through the mold-wheel and adjacent parts of a linotype-machine having my improvement embodied therein. Fig. 2 is an elevation looking edge-wise against the mold-wheel and adjacent 55 parts in the ejecting position, with the mold seated against the supports or banking-pieces. Fig. 3 is a horizontal section on the line 3 3 of Fig. 2. Fig. 4 is a face view looking forward from the face of the mold toward the 60 trimming-knives and adjacent parts. Fig. 5 is a horizontal section on the line 5 5 of Fig. 2.

Referring to the drawings, A represents the slotted mold, rigidly secured in the vertical wheel B, which is mounted to turn on an arm extending laterally on the horizontal slide C. 70 The mold-disk receives an intermittent rotation from the driving-pinion D, and the slide C is moved forward and back by the usual cam mechanism, first, when the mold is in the casting position, and, second, when it is 75 in position for the ejection of the slug.

E represents the stationary back knife for trimming the base of the slug as it is carried by the passing mold.

F F represent the two vertical parallel 80 knives, located directly in front of the mold, for the purpose of removing any fins or burs from the forward edge of the outgoing slug, insuring the uniform thickness of its body portion.

G represents the horizontal ejector-blade, guided in the frame behind the mold-wheel and operated by the usual connections. After the slug has been cast in the mold the disk revolves, carrying the mold and the contained 90 slug past the edge of the knife E, which trims the base of the slug flush with the mold. The disk continues its rotation until the mold assumes a vertical position directly between the ejector-blade and the front trimming-knives, as shown in Fig. 1. As soon as the casting operation is completed the mold-wheel and mold are drawn rearward by the movement of the slide C in order to draw the 95 letters or characters on the front edge of the 100

slug out of the matrices and in order also to bring the wheel in position to carry the rear face of the mold closely against the back knife E. When the mold has reached the 5 ejecting position, (shown in Fig. 1,) it is carried forward by the movement of the slide C in order to present its front edge and the contained slug as near as possible to the edges of the knives F, so that the slug may be accurately guided between them.

The foregoing parts are constructed and operate in the ordinary manner.

During the ejection of the slug the mold A, which is built up of several parts, is unsupported at the front or, in other words, is supported wholly by the wheel to which its body portion is screwed. When, therefore, the pressure is applied by the ejector to expel the slug, there is a tendency to spring the mold 15 forward, to push the mold forward out of the disk, and to push the cap or outer portion of the mold away from the lower portion. It is to overcome this difficulty that my invention 20 is intended.

25 In the form shown my improvement consists of two lugs or banking-pieces II, rigidly seated in the main frame of the machine, preferably beyond the ends of the side knives F, and in such position as to afford a direct support or bearing for the two ends of the mold 30 at the front side.

It will be observed that when the mold reaches the ejecting position and is carried forward both its cap and its body portion 35 bear at the two ends on their front faces firmly against the supports I. When the mold is thus supported, it is prevented from springing forward, and consequently the wheel is relieved from strain and the pressure 40 prevented from displacing the mold or separating its members.

The essence of the invention lies in providing firm supports against which the mold as a whole may be seated and sustained during the ejection of the slug, and it is manifest that the support may be varied in form and arrangement at will, provided only it has the mode of action above described. It is manifestly immaterial whether the supports are separately constructed and applied 15 to the frame, or whether they are made in one piece, or whether they are simply suitable surfaces formed integral with the frame.

Having described my invention, what I claim is—

1. In a linotype-machine, a mold and a slug-ejector, in combination with means for rigidly supporting the mold against the thrust of the ejector.

2. In combination with the wheel and the mold mounted therein, an ejector to expel the slug, and front supports against which the ends of the mold bear during the action of the ejector.

3. In a linotype-machine, a mold movable 65 in the direction in which the slug is ejected, a blade acting from the rear to eject the slug, and a fixed front support to sustain the mold bodily in opposition to the thrust of the ejector.

4. In a linotype-machine and in combination, the ejector, the sectional mold, and rigid means bearing against both the cap and body sections of the mold to sustain them against the thrust of the ejector.

In testimony whereof I hereunto set my hand, this 29th day of May, 1903, in the presence of two attesting witnesses.

PHILIP T. DODGE.
